US0D1066325S

(12) **United States Design Patent** (10) **Patent No.:** **US D1,066,325 S**
(45) **Date of Patent:** **** Mar. 11, 2025**

(54) **DISPLAY DEVICE**

(71) Applicant: **Samsung Display Co., Ltd.**, Yongin-si (KR)

(72) Inventors: **Yun Joo Yim**, Yongin-si (KR); **Hyeon Sook Jeong**, Yongin-si (KR)

(73) Assignee: **Samsung Display Co., Ltd.**, Yongin-si (KR)

(**) Term: **15 Years**

(21) Appl. No.: **29/867,257**

(22) Filed: **Oct. 17, 2022**

(30) **Foreign Application Priority Data**

Apr. 18, 2022 (KR) 30-2022-0015203
Sep. 29, 2022 (KR) 30-2022-0040041

(51) **LOC (15) Cl.** **14-02**

(52) **U.S. Cl.**

(57) **CLAIM**

The ornamental design for a display device, as shown and described.

DESCRIPTION

FIG. 1 is a front perspective view of the display device according to a first embodiment;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the display device according to a second embodiment;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof; and,

FIG. 15 is a rear perspective view thereof.

The broken lines in the figures depict portions of the display device that form no part of the claimed design.

The “smart OLED viewer” mark, as shown in FIGS. 10 and 15 of the claimed design, is a registered trademark of Samsung Display Co., Ltd.
